ELECTRICAL CONDUCTOR

Donald H. Scofield, Redwood City, Calif., assignor to Insul-8-Corp., San Carlos, Calif., a corporation of California

Filed June 16, 1958, Ser. No. 742,075

1 Claim. (Cl. 174—117)

This invention relates broadly to electrical distribution systems and, more particularly, to electrical conductors for use in such systems.

It has heretofore been proposed, and is now known, to provide rigid or semi-rigid wires, cables, bars and the like across or through an area within which electrical energy must be supplied to one or more devices such as appliances, tools, machines and the like. Such a conductor is supplied with electricity from a suitable source and is tapped at one or more points along its length to provide electrical energy to the devices referred to. In my co-pending application Serial No. 803,878, filed April 3, 1959, entitled Electrical Distribution System, there is disclosed and claimed such a system, and in the present application I disclose and claim a conductor of new and improved structure for use in such a system and by reason of which improved operation is achieved.

The invention is described in the following specification and illustrated in the accompanying drawing in which:

FIG. 1 is a perspective view of a preferred form of conductor provided by the invention;

FIG. 2 is an elevational view showing a tap-off device applied to the conductor of FIG. 1;

FIG. 3 is a perspective view of a second embodiment of the invention, and

FIG. 4 is a part elevational part sectional view showing a tap-off device applied to the conductor of FIG. 3.

Electrical distribution systems of the type to which this invention relates are well known and, in general, comprise an electrical conductor which is suitably supported at one or more points along its length and is tapped to provide electrical energy to an electrically operated device, such as a portable tool, lighting fixture or the like.

The invention provides an electrical conductor of new and improved construction by reason of which improved and simplified tap-off means may be used to transmit electricity from the conductor to a device to be operated. A preferred embodiment of the new and improved conductor is disclosed in FIGS. 1 and 2 and comprises an elongated cable-like element formed of electrically non-conductive material such as a plastic, hard rubber or the like. This conductor is of uniform cross section throughout its length and this cross section comprises a central part 2 defined by substantially parallel upper and lower walls 4, 6. At each side of this central part there is a part of outwardly decreasing thickness defined, on one side of the central part, by the outwardly converging upper and lower walls 8, 10 and on the other side by the outwardly converging upper and lower walls 12, 14. The upper and lower walls on each side of the central part 2 stop short of juncture and are connected at their outer edges by the side walls 16, 18 each of which is formed with a central inwardly extending groove 20 which extends longitudinally of the conductor throughout its length.

Means are provided by the invention for imparting strength and rigidity to the elongated conductor and such means comprise an elongated, relatively stiff member 20 which is embedded in the enlarged central part 2 of the conductor and which extends from end to end thereof. In the disclosed embodiments of the invention this

2

member is a twisted, multi-strand wire rope, which is disposed midway between the upper and lower walls 4, 6 and centrally between the side walls 16, 18.

Means are also provided by the invention for providing electrical energy along the length of the conductor and such means comprise the elongated electrically conductive wires 30, 32 which are respectively disposed within the side parts of the conductor which are defined, respectively, by the walls 8, 10, 16 on one side and walls 12, 14, 18 on the other. Each of these wires, which may be of stranded construction, extends throughout the length of the conductor in spaced and parallel relation to the central supporting and stiffening cable 20 and on the opposite sides thereof.

15 In accordance with an important feature of the invention each of the conductive wires 30, 32 is positioned inward of, and closely adjacent, the bottom of the groove 20 which is formed in a side wall 16, 18. Thus, each wire is covered on its outer surface, i.e., the surface removed from the strengthening and stiffening member 20, by only a very thin membrane 40 which may be easily punctured when it is desired to make contact with the conductors in order to supply electricity from them to a device which is to be operated.

25 A tap-off device for connecting the two conductors 30, 32 to such a device to be operated is illustrated in FIG. 3, in which there is shown a power take-off device the construction of which forms no part of the present invention but is disclosed and claimed in the co-pending application

30 referred to above. It will be seen, from FIG. 2 and from the co-pending application, that this take-off device comprises two parts 50, 52 which are brought together in clamping relation to the conductor and that these parts include pointed contact members 54, 56 which, when the

35 take-off device is in clamping engagement with the conductor, are positioned and operable to pierce the two membranes 40 and engage the conductive wires 30, 32. These contact members 54, 56 are connected to leads

40 which conduct electricity to the device which is to be operated. The power take-off device also includes a pointed ground contact member 58 which is positioned and operable, when the power take-off device is in clamping relation to the conductor, to pierce the non-conductive material forming the central part of the conductor and engage the strengthening and stiffening member 20 in order to provide a ground contact. This penetration of the central part of the conductor to the member 20 is preferably made through the wall 6.

45 The plastic or other non-conductive material from which the central and side parts of the conductor are made is a unitary, integral structure which may be manufactured by an extrusion process and, in effecting this, the material may be extruded directly about the strengthening and stiffening member 20 and the conductive wires 30, 32.

50 A second embodiment of the invention is disclosed in FIGS. 3 and 4 of the drawings and, like the embodiment disclosed in FIGS. 1 and 2, comprises an elongated, cable-like body formed of electrically non-conductive material.

55 This body is of uniform cross-sectional shape throughout its length and at each point along its length its cross section comprises a central annular part 60 which extends throughout the length of the conductor and has a substantially circular opening therein. A pair of converging arms 62, 64 extend outwardly from one side of the central part 60 and a second part of converging arms 66, 68 extend outwardly from the opposite side of the central part. The arms of each pair converge outwardly from the upper and lower parts of the central part 60 and therefore each pair of arms defines an opening or

70 72 which extends throughout the length of

the conductor. The arms of each pair substantially engage each other at or adjacent their outer ends and the arms are formed of a material which permits them to have some flexibility whereby they may be spread slightly in order to give access to the opening 70 or 72 between the arms.

A stiffening and strengthening member 74, which may be a stranded wire rope, is disposed within the opening in the central part 60 and extends throughout the length of the conductor. Electrically conductive wires 76, 78 are disposed within the openings 70, 72 which are defined by the arms of each pair of arms, and these wires extend throughout the length of the conductor.

In FIG. 4 of the drawings there is illustrated a power take-off device in operative relation to the conductor disclosed in FIG. 4. This take-off device includes, among other parts, two pointed contact members 92, 94 which, when the take-off device is in operative clamping relation to the conductor, pass between the arms 62, 64 on one side of the conductor and between the arms 66, 68 on the other side into electrical contact engagement with the wires 76, 78. The take-off device also includes a ground contact member 96 and when the tap-off device is in operative clamping relation to the conductor this ground contact member penetrates the wall of the central part 60 of the conductor to engage the strengthening and stiffening member 74 and effect a ground connection.

It is believed that the use and operation of conductors according to the invention will be fully understood from the foregoing description. Conductors as described and illustrated in this specification, and according to the invention, may be easily and cheaply manufactured by an extrusion process but will be strong and sufficiently rigid, because of the incorporation therein of the central strengthening and stiffening member, to support any desired number of power take-off members and their associated leads. These conductors, including as they do electrically conductive wires which are normally surrounded and protected by the structure of the conductor itself, permit easy and quick take-off of electricity by reason of the fact that the part of the conductor which surrounds and protects the wires may be easily and quickly pierced or penetrated to give access to the wires. The conductor also is so constructed that it may be easily and quickly hung or otherwise installed by known devices.

While I have described and illustrated certain embodi-

ments of my invention it will be apparent to those skilled in the art that other embodiments, as well as modifications of those disclosed, may be made and practised without departing in any way from the spirit and scope of the invention, for the limits of which reference must be made to the appended claims.

What is claimed is:

An electrical conductor structure constructed and intended to be suspended for engagement by contact members, comprising an elongated, unitary cable-like body formed of electrically non-conductive material, said body at each cross section throughout its length having an enlarged central part comprising substantially parallel upper and lower parts and oppositely extending side parts, each of said side parts being defined by upper and lower walls which converge outwardly from the central part to define an elongated channel extending the length of the side edges of the body, an elongated cable-like supporting member of substantial strength and rigidity embedded within said central part and extending substantially throughout the length of the elongated body and positioned therein to be engaged by a contact member piercing the non-conductive material of the cable-like body, and an elongated electrical conductor wire embedded in each of said side parts on opposite sides of said cable-like supporting member and extending substantially throughout the length of the elongated body and adapted to be engaged by electrical contact members piercing the non-conductive material of the cable-like body, each conductor wire lying adjacent the bottom of the said elongated channel.
